UNITED STATES PATENT OFFICE.

THADDEUS B. KEELER, OF DANBURY, CONNECTICUT.

MAST-ARM FOR ELECTRIC LAMPS.

SPECIFICATION forming part of Letters Patent No. 355,400, dated January 4, 1887.

Application filed April 22, 1886. Serial No. 199,746. (No model.)

To all whom it may concern:

Be it known that I, THADDEUS B. KEELER, a citizen of the United States, residing at Danbury, in the county of Fairfield and State of Connecticut, have invented certain new and useful Improvements in Mast-Arms for Electric Lamps; and I do hereby declare the following to be a full, clear, and exact description of the invention, such as will enable others skilled in the art to which it appertains to make and use the same.

My invention has for its object to produce a device which will enable electric lamps to be lowered when it is desired to clean them or to renew the carbons, and by which they may be readily restored to position for use.

In carrying out my invention I so balance the parts that the lamp is retained in either its raised or lowered position without other devices. I thus avoid any special or severe strain upon the cords which sustain the lamp. I have, furthermore, provided a special device which will catch the lamp and prevent its falling in the event of the breaking of either or both of the cords when the lamp is in its raised position. These results I am enabled to accomplish by means of the novel construction and arrangement of parts, of which the following description, in connection with the accompanying drawings, is a specification, numbers being used to indicate the several parts of the device.

Figure 1 is a side elevation of the device complete, the position of the parts being shown in full lines when the lamp is in its raised position and in dotted lines when it is at its lowered position; Fig. 2, a rear view of the top of the mast, and Fig. 3 is a front view of the outer end of the arm.

I have shown my improvements in connection with an ordinary mast. It will be apparent, however, that my invention is equally applicable, with slight changes in the details of construction, to lamps suspended from arms projecting from the sides of buildings.

1 represents the mast, 2 the mast-arm, and 3 braces and trusses of ordinary construction for imparting strength and rigidity to the mast-arm. The arm is of course made solid

with the mast, and at its outer end is provided with a head, 4, which is attached thereto in any suitable manner.

5 is a track, the outer end of which is pivoted to the head, and which is provided at its inner end with a stop, 6, the purpose of which will presently be explained. This track lies between the pair of braces, (one only being shown,) which extend from the mast to the arm, the braces acting as a guide to the track as it is raised and lowered, and also serving to hold it in place when at its raised position. As shown in Fig. 3, the outer end of the track is bifurcated, branches thereof being pivoted on opposite sides of the head.

7 is a pulley pivoted in the head at the outer end of the arm.

8 indicates curved arms, which are attached to the head and extend inward below the track when in its raised position, the functions of which will presently be explained. A single bolt, 9, passing through the curved arms, the branches of the track, the head, and pulley 7, serves to secure these parts in operative position, the curved arms being additionally secured to the head by one or more bolts, as shown, whereby they are prevented from turning.

10 indicates an electric lamp of any construction, and 11 a cross-piece which serves to engage arms 8 should the suspending-cord be broken, as will be more fully explained.

12 indicates a pulley, which is journaled on cross-piece 11, and is adapted to travel upon track 5, and from which the lamp is suspended.

14 is a weight which serves as a counter-balance to the lamp.

15 and 16 indicate two cords that pass upward from the weight, and over a double pulley, 17, at the top of the mast. The mast-arm is preferably provided with a central opening, 18. Cord 15 passes straight forward from pulley 17, through the mast, and through the mast-arm, then over pulley 7, and is attached in any suitable manner to cross-piece 11, which also serves as a journal for pulley 12. The other cord, which I have indicated by 16, passes through the mast, then over a

pulley, 20, upon the opposite side thereof, and is attached to the inner end of track 5. As it is convenient in use to have cords depending from the inner end of track 5, and from the 5 weight, as a means for operating the device, I preferably extend cord 16 downward and attach its other end also to the weight, as is clearly shown in Fig. 1.

21 indicates the current-wires, which, however, for the sake of clearness, I have only shown as extending from the pole to the lamp. These current-wires form no portion of my invention, and it will of course be understood that the connections may be made in the ordinary 10 or in any preferred manner. The position assumed by the current-wires when the lamp is in its lowered position is clearly shown by dotted lines in Fig. 1.

As stated above, the weight is so regulated 20 as to serve as a perfect counter-balance for the lamp—that is to say, when both weight and lamp are in a position half-way between the positions at which they are as shown in full and in dotted lines, each will balance the other. 25 When, therefore, the weight is moved below this position, it will act to carry the lamp to its raised position, and when the weight is raised above this position it will allow the lamp to move to its lowered position. It will 30 of course be apparent that the operations of lowering or raising the lamp may be perfectly and easily controlled by cord 16. Stop 6 at the inner end of the track catches pulley 12 when it has reached its lowest position, and 35 holds it, thus preventing the lamp from passing off the track.

In order to avoid the possibility of the lamp falling to the ground should either or both of the cords become broken, I have provided 40 curved arms 8, which catch it and hold it by means of cross-piece 11. Should cord 16 become broken, the inner end of the track would of course drop instantly. It would, however, swing inward between these arms, so that there 45 would be no possibility of the lamp running down the track, as the cross-piece 11 would catch upon these arms 8.

In order to insure that pulley 12 shall always travel down the track as it is lowered, I 50 provide a cord or wire, 22, which is attached at one end to cross-piece 11, and which extends along over the track, between the supporting-braces, through stop 6, which is preferably provided with a pulley, (not shown,) and the 55 inner end of which is attached to the mast. There can be no trouble of this kind unless the track is icy. This danger is wholly avoided, however, by the use of cord or wire 22. As the inner end of the track drops down, the cord 60 or wire is necessarily pulled down also, it sliding freely through the stop, thus compelling pulley 12, from which the lamp is suspended, to travel down the track.

It will of course be understood that the 65 tails of construction may be considerably va-

ried without departing from the spirit of my invention.

I claim—

1. A rigid arm and a track pivoted at the outer end thereof, in combination with the 70 weight and two cords extending upward therefrom, one of which is attached to a pulley, from which the lamp is suspended, and which is adapted to travel upon the track, the other passing to the inner end of said track, whereby 75 when said weight is raised the inner end of the track is permitted to fall and the lamp to move downward thereon.

2. The rigid arm and a track pivoted at the outer end thereof, in combination with pulley 80 12, which is adapted to travel on said track, and from which the lamp is suspended, weight 14, and two cords passing upward from said weight, one of which is attached to said pulley and the other to the inner end of the track. 85

3. The arm, track 5, pivoted at the outer end thereof and having at its inner end a stop, and a pulley adapted to travel on said track, in combination with a weight and two cords passing upward therefrom, one of which extends to said pulley, the other to the inner end 90 of the track.

4. The arm, track 5, pivoted at the outer end thereof, and pulley 12, adapted to travel on said track, and from which the lamp is 95 suspended, in combination with a cord, 15, extending upward from the weight, then along the arm to the lamp, and a cord, 16, which extends upward, is attached to the inner end of the track, and then extends downward again, 100 and is a second time attached to the weight.

5. The arm, track 5, pivoted thereto, and a pulley, 12, adapted to travel on said track, in combination with the weight, cord 15, which passes from said weight over pulley 17, through 105 the arm, then over pulley 7, and to pulley 12, and cord 16, which extends over pulleys 17 and 20, is attached to the inner end of the track, and then extends downward and is a second time attached to the weight. 110

6. The arm, the track pivoted at the outer end thereof, and pulley 12, adapted to travel on said track, in combination with curved arms 8, an electric lamp having a cross-piece, 11, weight 14, and cords extending upward 115 therefrom, one of which is secured to pulley 12 and the other to the inner end of the track, whereby, should either cord break, the lamp will be caught by the engagement of the cross-piece with arms 8. 120

7. The arm having at its outer end head 4, the track pivoted to said head, and arms 8, secured thereto, in combination with the lamp, pulley 12, the cross-piece 11, weight 14, and cords 15 and 16. 125

8. The arm having head 4, the track pivoted thereto and having a stop, 6, at its outer end, in combination with pulley 12, adapted to travel on said track and to carry a lamp, a weight adapted to counterbalance said lamp, 130

and cords 15 and 16, one of which passes from the weight to said lamp, the other passing to the inner end of said track, then downward to the weight again.

5. The arm, the track pivoted thereto and having stop 6 at its free end, and pulley 12, from which the lamp is suspended, in combination with a cord, 22, extending from the journal of said pulley through stop 6, and

whose inner end is attached to the mast, where- 10
by said pulley is caused to travel down the track as it is lowered.

In testimony whereof I affix my signature in presence of two witnesses.

THADDEUS B. KEELER.
